DESIGN FOR A NIB SECTION FOR A FOUNTAIN PEN OR SIMILAR ARTICLE

Arthur Winter, Weehawken, N. J.

Application April 4, 1945, Serial No. 118,852

Term of patent 14 years

(Cl. D74—1)

To all whom it may concern:

Be it known that I, Arthur Winter, a citizen of the United States of America and a resident of Weehawken, in the county of Hudson and State of New Jersey, have invented a new, original, and ornamental Design for a Nib Section for a Fountain Pen or Similar Article, of which the following is a specification, reference being had to the accompanying drawing, forming part thereof, in which—

Fig. 1 is a horizontal side elevational view of a nib section for a fountain pen showing my new design.

Fig. 2 is a bottom plan view of the same;
Fig. 3 is a top plan view of the same.

I claim:

The ornamental design for a nib section for a fountain pen or similar article, as shown.

ARTHUR WINTER.
